UNITED STATES PATENT OFFICE.

LOUIS A. KRAMER, OF CHICAGO, ILLINOIS.

HOG-DEHAIRING MACHINE.

Application filed September 24, 1925. Serial No. 58,245.

My invention relates to carcass dehairing machines of the general class employed for dehairing, scraping and massaging freshly killed hogs.

5 In one of its numerous aspects, my invention aims to provide a machine for this purpose which will be unusually compact in proportion to its hog cleaning capacity per hour, and one which can readily be increased in capacity by merely increasing the 10 number of counterpart sections.

In another aspect, my invention provides a novel method of manipulating the hog during its dehairing so as to insure an effective 15 cleaning without damaging any part of the hog.

More particularly, my invention provides a dehairing machine in which the hog is rotated while it is passing transversely of its 20 axis through the machine, and in which the hog is supported entirely by rotating members while in the field of the dehairing operation.

In the machines heretofore employed and 25 designed for operating on a hog moving transversely of its axis through the machine, the hog has been supported either entirely or at least partly by stationary elements (such as bent or inclined bars or 30 platform supports) or by elements (such as conveyers) which moved quite slowly. In practice, the friction of the hog against such stationary or slowly moving parts often causes an undue abrasion of the 35 surface of the skin portions engaged by these parts. Furthermore, with any flabby or small hogs, portions thereof will sag between adjacent stationary or slowly moving supporting elements, thereby interfering 40 with the uniformity of the cleaning and dehairing and frequently causing such hog portions to be cut. In my present machine, I aim to avoid all of these difficulties by 45 having the hog supported throughout its dehairing by continuously and rapidly moving elements which will prevent both such sagging and such abrasion.

Furthermore, my invention provides an 50 arrangement for this purpose in which the hog is continually rotated at a considerable speed while it is being dehaired, thereby enabling the cleaning action to be effected with strokes of such relative lightness as not to affect the texture of the bacon which

is afterwards cured from outer portions of the hog. It also provides an arrangement in which the cleaning of a hog passing horizontally through a machine can be effected with relatively slight vertical movements of the hog, thereby preventing such undesirably hard slamming as would be apt to effect both the skin of the hog and the fat adjacent to the skin.

In some further aspects, my invention provides a machine in which continuously rotating elements arranged for supporting the hog are so closely spaced as to avoid having the fat or legs of the hog caught between them and also to prevent portions of unusually small hogs from becoming jammed or caught, thus eliminating the cutting of hog portions as commonly experienced with machines heretofore in use. Furthermore, my invention provides a machine in which the hog is continuously fed through the field of the dehairing at a predetermined rate and in which the feeding of the hog is entirely independent of the supporting thereof. It also provides a machine which can readily be constructed either with or without auxiliary dehairing members above the main dehairing members which cooperate with other rotating elements in supporting and continuously rotating the hog while passing through the field of the dehairing operation. Still further and also more detailed objects will appear from the following specification and from the accompanying drawings, in which—

Fig. 1 is a side elevation of a machine embodying my invention, the scalding tank and the delivery conveyer being shown in dotted lines.

Fig. 2 is a plan view of the same machine with portions of the top broken away and with parts of the mechanism omitted for the sake of clearance.

Fig. 3 is an enlarged vertical section taken transversely of the machine along the line 3—3 of Fig. 2.

Fig. 4 is an enlarged and fragmentary vertical section taken along the line 4—4 of Fig. 3 to show the arrangement of the beaters and collars on consecutive shafts and the disposition of the feeding means with respect to these collars and beaters.

Fig. 5 is a view similar to Fig. 4, showing the arrangement of the corresponding parts

in a machine embodying my invention and having beater members only on alternate shafts.

Fig. 6 is a plan view of the parts shown in Fig. 5.

Fig. 7 is a horizontal section taken along the line 7—7 of Fig. 4 of one of the spools which are mounted on the shafts of the machine of Figs. 1 to 4 inclusive.

10 Illustrative of the method and means employed in my machine, Fig. 4 shows portions of the machine of Figs. 1 to 3 with a hog 1 in a position in which it is supported jointly by two disks or collars 3 which have 70 their peripheries closely adjacent to each other. These disks are respectively fastened to shafts 4 and 5 which are both rotated in the same (clockwise) direction, so that they both rotate the hog in a counterclockwise direction. The beaters 5 and 6 which are respectively carried by the shafts 4 and 5 also tend to rotate the hog in the same direction, and, since the scrapers 7 at the end of these beaters are at a considerably greater 75 distance from the axes of the corresponding shafts than the peripheries of the collars or disks which primarily support the hog, these scrapers will drag over the surface of the hog with a scraping action.

80 Each hog when fed into the machine is disposed between a pair of push arms 8 which are fastened to spaced links on the upper stretches of endless chains 9, these chain stretches being disposed above and parallel to the common plane in which the axes of the shafts are disposed and relatively near these axes, so as to be considerably below the said discs. This chain moves 85 continually in one direction transverse of the said shafts, so that an engagement of the hog by the push arms behind it will feed the hog positively transverse of the said shafts. However, the push arms on each chain are spaced by a distance greater than the maximum diameter of the carcasses for which the machine is to be employed, so as to leave freedom for transverse to-and-fro movement of the hog. Moreover, each 90 push arm preferably has an anti-friction wheel 10 pivoted in its upper end on an axis parallel to the said shafts, so as to prevent a hog from riding up on the corresponding arm when forced against the latter by the scrapers.

95 Owing to the close spacing of the discs on the consecutive shafts, the tendency of any flabby or small hog to sag between the discs on these shafts when in a position such as that shown in Fig. 4 is reduced, and this tendency is further nullified by the continuous rotating of the hog. Consequently, the hog at no time can sag or jam between these discs so as to permit any of the beaters 5 or scrapers 7 to impact to an undue extent against such a portion of the hog.

So also, the continuous rotating of the hog in the same direction in which the scrapers move along its surface reduces the rate of movement of the scraper over the engaged surface of the hog, so that I secure a relatively light but positive scraping action even when a beater is bent back as shown at 5^A.

100 By disposing the operative stretch of the chain 9 considerably below the tops of the discs 2 and 3, I keep this chain out of contact with the hog, so that the latter is supported at all times by continuously moving elements—which may include the beater straps or scrapers when the hog is in certain positions—and does not drag or scrape along any stationary surfaces. Hence I entirely avoid the damaging hog portions which commonly occurs when the hog is supported either primarily or entirely by 105 stationary or slowly moving members.

To reach the full length of the hog, I provide a large number of beater members on each shaft, these being desirably spaced uniformly along the shaft. I also (may) 110 mount the beaters on adjacent shafts in a staggered relation to each other, thereby enabling me to employ beaters of considerable reach with a relatively close spacing of the shafts. As a desirable mounting for the beaters, I may employ spools constructed substantially as shown in Fig. 7, so that each spool includes a pair of discs 2 spaced by a cylinder 11 provided with arms 12 to which the beater straps are fastened, and a pair of outwardly projecting hub ends 13. With the said staggered arrangement of the beater members on adjacent shafts, I alternate such beater-carrying spools with plain spools 14 as shown in Fig. 5, and by abutting the hub ends of adjacent spools against each other as shown in the same figure, I can use these hubs for limiting the downward movement of the chain 9 interposed between the corresponding spools so as to take up the sag in the chain. Since the upper parts of these hubs rotate in the same direction in which the adjacent stretch of the chain travels and since the small diameter of the hubs reduces the rate of movement at their periphery, their contact with the chains will afford but little friction, so that I can readily employ the hubs as chain supports.

115 For quantity hog dehairing, I desirably build my machine in a series of sections, each of which is here shown as including two of the said shafts, so that I can vary the effective capacity of the machine by varying the number of these sections, three of which sections are designated in Fig. 1 as A, B, and C. To make the capacity of the machine still greater in proportion to its floor spacing, I may also provide auxiliary beater mechanisms and for this purpose preferably 120

provide shafts 15 disposed above the common plane of the main beater-carrying shafts, each of these elevated shafts being preferably midway between the constituents of one consecutive pair of the lower or main beater-carrying shafts as shown in Fig. 1. These elevated shafts 15 preferably rotate in the same direction as the said lower shafts, so that the beaters 16 carried by the upper shafts will tend to rotate the hog in the same direction in which it is rotated by the spool ends or disks and by the lower beaters. Moreover, the upper beaters 16 desirably are greater in length than the lower ones, so as to give a lighter but more rapid impact against the hog.

To feed the hogs into the machine, I am here showing an inclined conveyer 17 leading upward from the scalding tank 18 and carrying push arms 19. These push arms are spaced along the conveyer by the same distances as those on the chain 9, so that the consecutive push arms on the conveyer will deliver hogs respectively into the spaces between consecutive push arms 8 on the feed chain 9. Then I provide a chute plate 20 at the rear end of the machine down which the clean hog is charged upon a delivery belt 21.

Since all of the shafts which extend transversely of the illustrated machine rotate in the same direction, these shafts can readily be driven simultaneously by a simple mechanism, as by employing a motor 22 driving a horizontal shaft 23 and operatively connected to the upper shafts 15 by intermeshing gears 24 and 25. Then I can connect each of these upper shafts by a chain 26 to a pair of lower shafts as shown in dotted lines in Fig. 1 and in full lines in Fig. 3, so as to rotate all of the shafts simultaneously.

However, while I have heretofore described my invention in a highly desirable embodiment, I do not wish to be limited to the details of the construction and arrangement thus disclosed, since these might obviously be varied in many ways without departing either from the spirit of my invention or from the appended claims.

For example, Figs. 5 and 6 show a modification in which beater carrying shafts 28 and 29 have the beater members 30 on them in alignment with each other and closely adjacent longitudinally of each shaft, and in which an intermediate shaft 31 carries plain spools 32 which are not provided with any beater members. Comparing Figs. 5 and 6, it will be obvious that the spool ends or discs operate similarly in each case for rotating the hog continuously, and that by spacing the ends of adjacent spools on each shaft relatively close to each other and also to the adjacent beaters, I reduce the gap so that no leg or other portion of a hog can become caught. So also, it will be evident

from Fig. 4 that the hog will be fed successively over the spool ends or discs on the several shafts with only slight vertical movements, thereby preventing the damaging of hog portions which often occurs in machines designed for lifting the hog through a considerable distance and then permitting it to drop by gravity.

I claim as my invention:

1. A hog dehairing machine comprising a plurality of rotatable members having parallel axes and spaced so as to continuously support a hog disposed lengthwise of the said axes, dehairing means carried by certain of the rotatable members, means for continuously rotating all of the said members, and means separate from the rotating members for pushing the hog transversely of the said axes through the machine.

2. A hog dehairing machine as per claim 1, in which the feeding means comprise an endless member disposed so as to be out of engagement with the hog during the dehairing operation, and push means carried by the endless member for engaging the hog.

3. A hog dehairing machine as per claim 1, in which the feeding means comprise a plurality of chains disposed so as to be out of engagement with the hog during the dehairing operation, means for moving the chains conjointly in the same direction, and push members respectively carried by the several chains and disposed for engaging the hog, the push members on the several chains being arranged in groups aligned transversely of the chains.

4. A hog dehairing machine as per claim 1, in which the axes of the rotatable members are disposed in a common plane.

5. A hog dehairing machine as per claim 1, in which the axes of the rotatable members are disposed in a common horizontal plane.

6. A hog dehairing machine as per claim 1, in combination with auxiliary dehairing means disposed above the said rotatable members.

7. A hog dehairing machine comprising a plurality of parallel shafts, a plurality of dehairing means mounted on each shaft and spaced longitudinally of the shaft, means for continuously rotating all of the shafts; feeding means for pushing a hog transversely past the successive shafts; and discs fast on the shafts and so proportioned in diameter to the spacings between the shafts as to support the hog independent of the feeding means.

8. A hog dehairing machine as per claim 7, in which the feeding means comprise stretches of chains moving above the shafts but below the tops of the discs, and push members fast on the chains and projecting above the discs.

9. A hog dehairing machine as per claim 1,

7, in which the dehairing means on each shaft are in staggered relation to those on the adjacent shaft.

10. A hog dehairing machine as per claim 5 7, in which the dehairing means on each shaft are in staggered relation to those on the adjacent shaft and in which each of the said dehairing means moves between discs on the shafts adjacent to the one carrying 10 the said means.

11. A hog dehairing machine as per claim 7, in which the feeding means are arranged for pushing the hog in the same direction in which the upper portions of the discs 15 rotate.

12. A hog dehairing machine comprising a plurality of parallel shafts, a plurality of dehairing means mounted on each shaft and spaced longitudinally of the shafts, means 20 for continuously rotating all of the shafts; feeding means for pushing a hog transversely past the successive shafts; and discs fast 25 on and spaced longitudinally along each shaft, the discs on consecutive shafts being in alinement and having their peripheries close to each other.

13. A hog dehairing machine comprising a plurality of parallel shafts, a series of counterpart spools fast on and spaced along 30 each shaft; each spool comprising a pair of discs connected by a cylinder and a hub projecting beyond one disc, the spools on the several shafts being spaced to aline them transversely of the shafts; dehairing members carried by certain of the spools, means 35 for rotating all of the shafts, and feeding means for pushing a hog transversely of the shafts through the machine while the hog is supported by the said discs and dehairing 40 members.

14. A hog dehairing machine as per claim 13, in which the feeding means include chains supported by the spool hubs and push members fast on the chains.

45. 15. A hog dehairing machine comprising a plurality of rotatable members having parallel axes disposed in a common and substantially horizontal plane, the said axes being spaced so that the said members will 50 continuously and entirely support a hog disposed lengthwise of the said axes while the hog is passing through the machine transversely of the said axes; certain of the said members having dehairing elements; auxiliary rotatable dehairing means disposed

above the said members; means for simultaneously rotating the said members and the auxiliary dehairing means in the same direction, and means separate from said members for feeding the hog transversely of the 60 said axes consecutively past the said rotatable members.

16. A hog dehairing machine comprising a plurality of rotatable members mounted on parallel shafts, the said members including 65 dehairing means on certain shafts and closely adjacent discs on all of the shafts, and means for simultaneously rotating all of the shafts.

17. A hog dehairing machine comprising 70 a plurality of parallel shafts, discs fastened to and spaced along each shaft, the shafts being spaced so that the discs may continuously support a hog disposed lengthwise of the shafts, means separate from the discs 75 for feeding the hog transversely of the shafts, and means for dehairing the hog during its said feeding.

18. A hog dehairing machine comprising 80 a plurality of parallel shafts, discs fastened to and spaced along each shaft, the shafts being spaced so that the discs may continuously support a hog disposed lengthwise of the shafts, means separate from the discs 85 for feeding the hog transversely of the shafts, and means for dehairing the hog during its said feeding, the dehairing means including two sets of dehairing mechanisms operating respectively on the upper and lower portions of the hog. 90

19. A hog dehairing machine as per claim 17, in which the dehairing means include main dehairing mechanisms carried by certain of the said shafts, and auxiliary dehairing means separate from all of the said 95 shafts and disposed for operating on the hog from above the latter.

20. A hog dehairing machine as per claim 17, in which the dehairing means include main dehairing mechanisms carried by certain of the said shafts, and auxiliary dehairing means separate from all of the said 100 shafts and disposed for operating on the hog from above the latter, the said main and auxiliary dehairing mechanisms being all arranged for rotating the hog in the same direction. 105

Signed at Chicago, Illinois, September 18th, 1925.

LOUIS A. KRAMER.
